UNITED STATES PATENT OFFICE.

HENRY D. HINCKLEY, OF HARTFORD, CONNECTICUT, ASSIGNOR, BY MESNE ASSIGNMENTS, TO THE R. & H. MANUFACTURING COMPANY, OF HARTFORD, CONNECTICUT, A CORPORATION OF CONNECTICUT.

VENDING-MACHINE.

1,171,953.

Specification of Letters Patent. Patented Feb. 15, 1916.

Application filed October 21, 1913. Serial No. 796,443.

To all whom it may concern:

Be it known that I, HENRY D. HINCKLEY, a citizen of the United States, residing at Hartford, in the county of Hartford and 5 State of Connecticut, have invented certain new and useful Improvements in Vending-Machines, of which the following is a specification.

This invention relates to vending-ma-10 chines.

A vending-machine involving my invention can be used for receiving and delivering articles of various kinds, the invention not being limited in this respect. I prefer 15 to associate with the vending-mechanism check-controlled mechanism, and a check used in conjunction with this particular element may be of any character, for instance a coin. As will be inferred there may be 20 cases where the check-controlled mechanism can be omitted.

One of the primary purposes in view is the provision of an article of the character noted which is simple in construction, easy 25 to operate and which cannot easily get out of order.

Another feature of the invention is the provision of an article-container and vending-mechanism directly supported thereby, 30 which can be mounted in and removed from a casing or housing as a unit.

The device possesses other features of novelty and advantage which with the foregoing will be stated at length in the following description wherein I will set forth in detail that one of the several embodiments 35 of the invention which I have selected for illustration in the drawings accompanying and forming part of the present specifica-40 tion, this disclosure being provided to enable those skilled in the art to practice the invention. From this it will be evident that I do not restrict myself to said showing; I may depart therefrom in several and ma-45 terial respects within the scope of the invention defined by the claims following said description.

Referring to said drawings: Figure 1 is a perspective view of a vending-machine in-50 volving my invention. Fig. 2 is a vertical, transverse section on the line 2—2 of Fig. 3, looking in the direction of the arrow, the weight and the articles to be vended being omitted. Fig. 3 is a front elevation of the

machine with the front plate of the casing 55 or housing removed. Fig. 4 is a view corresponding practically to Fig. 2, with the lower part of the machine omitted and showing the supporting and vending member in its extreme advanced position, and 60 also illustrating the article to be vended and the weight. Fig. 5 is a view corresponding substantially to Fig. 3 with the parts, however, in the positions they are represented as occupying in Fig. 4. Figs. 6 and 7 65 are sectional elevations of the intermediate portion of the machine, Fig. 6 showing the supporting and vending member in an intermediate position, and Fig. 7 showing said member locked in its extreme forward 70 position.

Like characters refer to like parts throughout the several views which it will be noted are on different scales.

The different parts are mounted in a suitable casing, that denoted in a general way by 2 serving approximately in this respect. Said casing or housing 2 is shown as being of oblong form and as comprising a back or body member 3 and a removable face or 80 front member as 4 which may be made from any desirable material, for instance sheet metal. At the upper end of the front 4 is a flange 5 equipped with a pendent tongue 6 to enter the slot 7 (Fig. 2) of the cross bar 8 85 attached by one or more rivets or otherwise, to the back of the body member 3, said front 4 being equipped at its lower end with a pivoted hasp 9 slotted to receive the staple 10 on the lower closed end of the body mem- 90 ber 3, the two parts of the casing being prevented from wrongful separation by a lock as 11 connected with the staple 10.

Any desirable means may be provided for mounting the casing 2 in place. In this cas- 95 ing 2 is preferably removably mounted an article-container and directly supported by the article-container is the vending-mechanism and when check-controlled mechanism is employed, this is also directly supported 100 by this container, the container with the one or more mechanisms thereby presenting a unit and being susceptible of mounting and dismounting as such. The advantage of this is that in case the machine becomes out of 105 order through a blocking of the vending-mechanism or of the check-controlled mechanism, it will be simply necessary to take out

the unit mentioned and substitute instead of it an operative one. There may, of course, be cases where the article-receiver or container and the one or more mechanisms mentioned may be otherwise related, although the removable mounting of the container and the direct support thereby of said mechanisms has its advantages, and is therefore preferred.

10 As will be understood any desirable container may be provided, although the one shown and denoted in a general way by 12 meets the necessary conditions. Said container 12 as represented consists of a channeled member or a part approximately U-shaped in cross section, by reason of which its loading or charging is facilitated. As illustrated the open side of this container or receiver 12 is at the front, although this might be otherwise. Fastened by screws or otherwise to the sides of the receiver or container 12 is a hollow or chambered foot-piece 13 which constitutes in effect a part of continuation of the container 15 and which might in fact be integral therewith. This foot-piece 13 comprises two sides, and a skeleton or open back, the sides of the foot-piece overlying the outer faces of the side flanges of the container 12 near the bottom of the latter where the two parts are united in the manner set forth. Fastened to the back of the body member 3 opposite the foot-piece 13, is a cross piece 14 provided with the headed members 15 consisting of screws, the back of the foot-piece 13 having open bottom slots 16 to pass over the shanks of the two screws 15, the headed screw 17 extending through a perforation near the upper edge of the receiver 12 and 20 tapped into the cross piece 8, being provided to prevent accidental displacement of the container. By removing the front 4 and taking out the screw 17, the container 12 with the parts carried thereby can be dis- 25 mounted.

To support and to also vend the articles in the container 12 any desirable means may be utilized, the rocking or oscillating member or block 18 serving satisfactorily in this connection and said part 18 being mounted for oscillation about midway of the receiver or container 12 from front to rear thereof; in fact the longitudinal axis of the receiver substantially intersects the center of motion of said part 18 which when in its normal position is disposed approximately horizontally to sustain all the articles to be vended. To prevent these articles from jumping from place as the stack descends, the sides of the receiver 12 may have narrow flanges 19 extending for practically the complete length of the receiver. The part 18 at one side of the foot-piece 13 may be supported by the screw 20 tapped into the former and supported for rocking motion

by the adjacent side of the latter, the other pivot consisting of the plain stud 21 (Figs. 3 and 5) rigid with the plate or block 18 and sustained for rocking movement by the other side or wall of the foot-piece and projecting through said last mentioned side. To the stud 21 is rigidly connected the crank arm 22 constituting a simple means for rocking said part 18. The means shown for operating said crank-arm will be hereinafter set forth.

Between the sides of and rigid with the foot-piece 13, is an inclined directing or guide member 23 which terminates at its lower end in a horizontal ledge 24 onto which an article delivered by the part 18 can be received after it has passed down the directing member 23. While I do not limit myself to any particular degree of motion of the rocking or oscillating member 18 I prefer that the same be through about a quarter of a circle, and positive means as will now appear are provided for insuring this result. Fastened to and rising from the cross piece 14 is the abutment or stop member 25 adapted to engage the part 18 when in its normal position, while when said part 18 has been moved forward the requisite extent, it strikes against an abutment or stop member 26 rigid with said cross piece 14 as shown best in Figs. 2, 4, 6 and 7. The part 18 is provided at its opposite sides with the depending semi-circular or segmental flanges 27 constituting a suitable barrier or guard and which prevent the article being delivered from passing back of the inclined directing member 23. Rising from the back of the supporting-and-vending member 18 is the flange 28 which as said part 18 is initially tipped forward passes under the second article in the container 12 to prevent the descent of the stack at this time. After the flange 28 has subserved its function, the rear portion or edge of the supporting-and-vending members itself directly sustains the stack as shown in Fig. 4. It will be clear that the part which sustains the articles to be vended also delivers the same, serving in this respect a double function. It will be assumed that the supporting-and-vending member 18 is in its normal position and that it is advanced through the operation of the crank arm 22 or otherwise. On the initial forward movement of the member 18 the flange 28 is moved under the second article of the stack, and beyond this point or when the member 18 assumes a certain inclination, the particular article thereon can pass therefrom onto the directing plate 23 from whence it falls to the ledge 24, the casing having a slot 29 in the front thereof by which access can be had to said article. As will hereinafter appear means are provided for returning the part 18 to its initial

position, provided of course that there be any articles in the machine. If there be not, the part 18 is preferably locked in its shifted or advanced position so as to prevent further action of the machine. The result in question, however, might be otherwise obtained.

In connection with the article-supporting-and-vending member 18 I prefer to provide means of a positive character which prevents lateral displacement of an article thereon during the initial part of the advancing or vending movement thereof or until the same has reached its discharging position as in case such action occurred the machine might be blocked at this point. The means for accomplishing this function may vary as to character, although that now to be described is satisfactory. Attached to the front of the foot-piece 13 and extending from side to side thereof is the plate 30 the lower edge of this plate being above the ledge 24 a distance sufficient to permit the free passage of an article therebetween. At the upper side of this plate 30 are duplicate lugs or ears 31 curved inward and which overlie the lowermost article on the part 18. As the latter is forwardly tipped these lugs by engaging the lowermost article, then separated in a measure from the pile or stack, prevent said particular article from moving sidewise or toward the front of the machine until such time as the article is intended to fall from the part 18. In other words the lugs in question with the body of the plate prevent, in a positive and certain manner premature movement of the article to be delivered or that directly supported by the part 18, until said article should be discharged.

In connection with the stack or pile of articles there is provided a follower, and although the same may be of any desirable type, the weight 32 answers satisfactorily in this connection, said weight being supported for non-tipping movement in the channeled container 2; in fact the weight is practically keyed in place, the result mentioned being aided by the wings 33 which rise from the body of the weight at its ends, said body and wings having a flatwise sliding engagement with the side walls of the container, with the back thereof and also with the flanges 19, by reason of which the weight is positively prevented from turning, owing to which the last article can be properly delivered, in that it will be squarely presented to the part 18 and thereby accurately discharged. Some other type of automatic follower might subserve the same function, although the weight is preferable.

As will be understood any desirable vending mechanism may be utilized, although that now to be described is satisfactory. Supported on one side of the container, the

right as shown in Figs. 3, 5, 6 and 7, is an elongated strip or bar 34, having near its ends the longitudinal guide slots 35 (shown best in Fig. 2) which receive the guide pins 36 which may as shown consist of screws 70 tapped into the container 12. From this it will be clear that the bar 34 has a straight up and down movement. Said strip or bar 34 is notched at its lower end as at 37 to receive the stud 38 on the crank arm 22, so 75 that when the strip 34 is lowered the crank arm will be operated to advance the member 18 and thus the delivery of the article on said part 18, provided a coin be introduced into the machine. Slidably connected 80 with the strip 34 is a second strip 40, the strip 40 receiving across it several guide lugs 41 on the companion strip 34 and having a finger-piece 42 extending through a slot 43 (Fig. 1) in the casing 2. This strip 85 or bar 34 can only, however, be operated through the intervention of a check, for instance a penny, and the means whereby this operation can be secured may vary, although that shown and now to be described is advantageous. The strip 34 is notched or recessed as at 44 to present a coin seat or support, the companion strip 40 overlying the notch or recess, this recessed portion 44 being normally opposite the coin-slot 45 in 90 the casing 2. Supported by the back portion of the container 12 is a stop member 46, the active portion of which consists of a flange 47 normally opposite the notch or aperture 44. The strip 40 is provided with a rigid pin 48 extending across the notch or recess 44 and engaging the upper wall of said recess. It will be assumed that a coin has been passed through the slot 45 and that it is in the aperture or notch 44, the coin 105 resting at this time against the flange 47 and also against the lower inclined wall of the notch 44, being in the path of movement of the pin 48; the coin, therefore, couples or clutches the two strips 34 and 40. When, 110 therefore, the outer strip 40 is lowered through the action of the finger piece 42 with a coin in place as set forth, the pin 48 will strike the coin and the coin in turn will cause the inner strip 34 to be lowered an 115 extent sufficient to give the member 18 through the described parts, a quarter turn, the coin during such motion traversing the flange 47 and just about the time the advancing movement of the member 18 is completed the coin will pass free of the flange 47 so that it can roll down the inclined bottom wall of the notch or recess 44 and fall 120 into the bottom of the casing 2.

Connected to the strip 40 and also to the exterior of the container 12 is a spring 40' which during the downward or advancing movement of the strip or bar 40, is stretched so as to return said bar to its original position. Simultaneously the strip 34 and the 130

article-supporting and dispensing member 18 will be returned to normal position due to engagement of the pin 48 on strip 40 with the upper wall of notch 44 in said strip 34. To the strip 40 the pull member 49 may be connected and depend, this pull member projecting through the bottom of the casing 2 and terminating in a ring or eye 50 to receive the finger, so that through 10 the rod 49, the vending-mechanism can be also operated provided a proper coin has been introduced into the machine.

I provide automatically operative means for positively holding the stack-supporting member 18 in an advanced position, when the stack is depleted or exhausted, and although this means may be of any suitable character, the same operates advantageously in connection with the weight 32. Said 20 weight as illustrated is provided with several pins 51 which when the last article has been vended, are adapted to engage behind the back of said part 18, to thus positively hold the latter in its shifted position 25 and to also hold the strip or bar 34 in its advanced position at which time the solid or uncut part of said strip or bar will be opposite the coin slot 45. The result is that the strip or bar 34 acts as a barrier or guard 30 to close said slot 45 when the machine is empty, and thus when this condition exists, prevent the introduction of any more coins into the machine.

It will be noted that the article container 35 12 practically fills the casing. In using the word "practically", I do not mean to imply that the container altogether fills the casing but rather that the relation between the two should be such as to insure sufficient 40 space between one side wall of the container and the adjacent side wall of the casing for the operating mechanism for the dispensing member or means of whatever character the same may be. The fact that this operating 45 mechanism is in the space set forth whether the container practically fills the casing or not, is in itself a feature of considerable advantage in that unusual compactness is insured, the lateral extent of the casing being in effect very small—slightly greater in 50 fact than the article container. It will be perceived that the upper surface of the supporting and vending member 18 is flat and that the front wall of said part is practically in the plane of the flat upper surface,

so that it requires but a very small amount of turning movement of said part 18 to effect the delivery of an article. In reality I can by less than a quarter of a turn of said part 18 obtain such delivery, the latter 60 occurring when the angle of the flat surface crosses the angle of repose of the particular article to be vended. This small movement of the part in question is highly advantageous. There are vending machines 65 comprising an oscillating drum pocketed to receive an article, but with these pocketed drums it is necessary that they make practically a half turn before the article can pass therefrom. 70

What I claim is:

1. In a vending machine, the combination of an elongated casing, an elongated article container removably mounted in the casing, an article support sustained by said container, means between the container and the casing operative on the advancing movement thereof to tip said article support and to permit the gravitation therefrom of the article directly sustained thereby, spring means connected with the container and said other means and tending constantly to retract the latter, and a manually operative device connected with said first mentioned means to advance the same, one side of the 80 casing having a longitudinal slot to receive manually operative device.

2. A vending machine comprising a casing, an article container removably mounted in said casing, an article support sustained by said container, means between the container and the casing operative on the advancing movement thereof to tip said article support and permit the gravitation 90 therefrom of the article directly sustained thereby, spring means connected with the container and said other means and tending constantly to retract the latter, and a manually operative device connected with said first mentioned means to advance the same, one side of the casing having a slot to receive and permit of the movement of said 95 manually operative device.

In testimony whereof I affix my signature in presence of two witnesses.

HENRY D. HINCKLEY.
